CALIFORNIA.

RETAINING-CLAMP FOR ELECTRIC CONDUITS.

1,288,902.

Specification of Letters Patent. Patented Dec. 24, 1918.

Application filed June 14, 1917. Serial No. 174,721.

To all whom it may concern:

Be it known that we, WILLIAM PAGE HYATT and WILLIS CAMPBELL STRINGER, citizens of the United States, residing at Sacramento, in the county of Sacramento, State of California, have invented certain new and useful Improvements in Retaining-Clamps for Electric Conduits; and we do declare the following to be a full, clear, and 10 exact description of the same, reference being had to the accompanying drawings, and to the characters of reference marked thereon, which form a part of this application.

This invention relates to improvements in 15 clamps for fixing and retaining electric conduits in switch boxes or other similar places. By our improved invention we aim to produce a clamp acting as a lever whereby if the cable draws in either direction the clamp 20 engages it and prevents its being moved relative to the receptacle. In addition to this the clamp effectively closes the openings in the receptacle and thereby confines any fire or spark which may originate in the 25 receptacle. Our improved clamp is likewise designed to require a minimum space within the receptacle and be easily and quickly installed or removed.

A further object of the invention is to 30 produce a simple and inexpensive device and yet one which will be exceedingly effective for the purposes for which it is designed.

These objects we accomplish by means of 35 such structure and relative arrangement of parts as will fully appear by a perusal of the following specification and claims.

In the drawings similar characters of reference indicate corresponding parts in the 40 several views.

Figure 1 is a side elevation of a receptacle partly broken out and in section to show the position of our improved clamp when it is engaged with the conduit.

Fig. 2 is an end view of the clamp in 45 position within the receptacle as it appears from the outside of the receptacle.

Fig. 3 is a perspective view of the clamp.

Fig. 4 is a perspective view of a modified 50 form of clamp from that shown in Fig. 3.

Referring now more particularly to the characters of reference on the drawings the numeral 1 designates the receptacle, 2 the conduit opening therein and 3 the electrical conduit which projects through the opening 55 2. Our improved clamp comprises a bifur-

cated plate 4 having a tongue 5 thereon projecting at a substantially acute angle from the plate 4 and provided with notches 6 intermediate such tongue 5 and plate 4. The space 7 between the bifurcations of the plate 4 is of a slightly less width than the diameter of the conduit 3 and terminates at its upper end in a semi-circular portion 8 of a diameter slightly less than the diameter of the conduit 3. In practice when the conduit 3 is passed through the opening 2 and it is desired to fix the same stationary therein, the tongue 5 is projected through the opening 2 and the bifurcated plate 4 is pressed over the conduit 3. When the clamp is being pressed through the opening 2 there is of course a slight resiliency to the conduit 3 and also the tongue 5 may be slightly resilient whereby that portion of the tongue 5 adjacent the notches 6 may be forced through the opening 2 at a point where the diameter of the opening is wider than the tongue 5 adjacent the notches 6. Then when the tongue 5 is completely positioned through the opening 2 and the clamp is released this slight resiliency of the parts raises the whole clamp so that the notches 6 receive and engage the edges of the opening 2.

Since the space 7 and the diameter of the curved portion 8 is slightly less than the corresponding diameter of the conduit 3 this causes the plate 4 to pinch against the conduit on the inside of the receptacle and the tongue 5 frictionally engages the same on the outside of the receptacle 1. The engagement of the notches 6 with the edges of the opening 2 forms a fulcrum which causes the clamp to pivot like a lever. Thus if the conduit 3 is pulled from the inside the clamp pivots and the tongue 5 frictionally engages the conduit and prevents its being moved. If the conduit 3 is pulled from the outside the reverse operation takes place and the bifurcated plate 4 becomes more strongly frictionally engaged with the conduit and prevents movement in that direction.

In Fig. 4 we have a modified form of clamp. In this form 4^a designates the bifurcated plate and 5^a the tongue. Instead of the notches 6 however, we provide a rib 6^a which when the clamp is positioned impinges against the side of the casing 1 adjacent the hole 2 and forms the fulcrum 110

point necessary to the successful operation of the device.

In addition to forming the fulcrum point of the clamp the notches 6 or the tongue 6^a likewise prevent the clamp from becoming loose from the receptacle or cable excepting when it is desired to remove the same.

From the foregoing description it will be readily seen that we have produced such a device as substantially fulfills the object of the invention as set forth herein.

While this specification sets forth in detail the present and preferred construction of the device and of the modification thereof, as described, still in practice such deviations from such detail may be resorted to as do not form a departure from the spirit of the invention as defined by the appended claims.

Having thus described our invention what we claim as new and useful and desire to secure by Letters Patent is:

1. A clamp for electrical conduits consisting of a bifurcated plate arranged to be frictionally engaged with the sides of the conduit transversely with respect to its axis, and a tongue extending at an angle to the plate and adapted to frictionally engage the conduit longitudinally thereof.

2. A clamp for electrical conduits comprising a bifurcated plate arranged to be frictionally engaged with the sides of the conduit transversely with respect to its axis, and a tongue extending at an angle to the plate and adapted to frictionally engage the conduit longitudinally thereof, the tongue being provided with notches adjacent the plate.

3. A clamp for electrical conduits comprising a bifurcated plate arranged to be frictionally engaged with the sides of the conduit transversely with respect to its axis, and a tongue extending at an angle to the plate and adapted to frictionally engage the conduit longitudinally thereof, and means arranged on the tongue adjacent the plate whereby the clamp may be fulcrumed against the sides of an orifice in a holder through which the conduit may be projected.

In testimony whereof, we affix our signatures in the presence of two witnesses.
